UNITED STATES PATENT OFFICE.

JAMES A. WALSH, OF INDIANAPOLIS, INDIANA, ASSIGNOR TO THE INDIANA MANUFACTURING COMPANY, OF SAME PLACE.

PNEUMATIC STACKER.

SPECIFICATION forming part of Letters Patent No. 638,191, dated November 28, 1899.

Application filed February 16, 1899. Serial No. 705,598. (No model.)

To all whom it may concern:

Be it known that I, JAMES A. WALSH, a citizen of the United States, residing at Indianapolis, in the county of Marion and State of 5 Indiana, have invented certain new and useful Improvements in Pneumatic Stackers, of which the following is a specification.

It sometimes happens in the threshing of grain, especially where the straw is slightly 10 damp or tough, that some of the kernels will not be fully separated by the action of the threshing-machine and will pass on out with the straw. Where that class of straw-delivering devices known as "pneumatic straw-stackers" are employed, especially that 15 variety where the straw is passed through a fan on its way to the discharging or delivery point, some of the grains which adhere to the straw under the above conditions are dislodged, but there has heretofore been no way 20 of saving them, and they have instead been passed on out with the straw into the straw-stack.

The object of my present invention is to 25 provide a means by which such dislodged grain or any grain which may by any other means, accidental or otherwise, continue on with the straw into the straw-stack may be saved; and it consists in the application of 30 a screen to some convenient portion of the straw-stacker structure, through which such grain may fall and be separated from the straw and then conducted back and discharged at some appropriate point.

35 In the construction of an apparatus embodying my invention I have placed this screen within the bottom of the trunk or chute of the straw-stacker; but it may obviously be placed at any point desired.

40 Referring to the accompanying drawings, which are made a part hereof, and on which similar letters of reference indicate similar parts, Figure 1 is a view of the rear portion of a threshing-machine with a pneumatic straw-stacker attached thereto, my invention being embodied therein. Fig. 2 is a longitudinal sectional view, as seen from the dotted line 2 2 in Fig. 3, of a fragment of the 45 trunk or chute of a pneumatic straw-stacker 50 provided with a screen in its bottom side arranged in a manner adopted by me in carry-

ing out my invention; Fig. 3, a horizontal sectional view as seen when looking downwardly from the dotted line 3 3 in Fig. 2; Fig. 4, a transverse sectional view on the dotted line 4 4 in Fig. 2; and Fig. 5, a detail fragmentary sectional view similar to a portion of Fig. 2, but on a much-enlarged scale.

55 In said drawings the portions marked A represent the fan-housing of a pneumatic straw-stacker, B the trunk or chute of a pneumatic straw-stacker as the same is ordinarily constructed, and C a screen appropriate to the carrying out of my invention.

60 The fan-housing A and trunk or chute B are or may be of any ordinary or desired form or construction. The exit b for the saved grain is in the construction shown placed at or near its lower end just under the rear portion of the screen.

70 The screen C may be of any form desired. I have shown it as constructed of sheet metal crimped transversely at intervals, giving it substantially a "saw-tooth" form, with the openings through which the grain in being 75 saved is to pass at or near the lowest points or within the "throats" of the "teeth." While, as above stated, such screens may be made in any form desired, I consider that the particular form shown has some special advantages. The straw in being projected through a pneumatic straw-stacker is driven with considerable force and at a considerable speed. A screen having the form shown presents a substantially smooth surface for the 80 straw to pass over and provides recesses into which the grain may fall and which protect whatever falls therein against the force of the blast of air. An ordinary wire screen might be used for this purpose and in my 85 opinion would prove reasonably effective; but grain which fell thereon would to some degree be subject to the force of the blast of air, and some portion of it might possibly be carried out with the straw instead of passing 90 through to below the screen. Then, too, such meshes are apt to permit some portion of the force of the air-blast through them and possibly prevent the grain from sliding back to the point of exit and are also liable to catch 95 short straws or the ends of straws, while a screen of the form shown is smooth on those

100

portions with which the straw comes in contact and its pockets or depressions create little eddies in the air-current, which facilitate the deposit of the loose grains. For the reasons given, therefore, I prefer a screen constructed as shown and described, although I do not desire to be understood as limiting myself to any particular form, arrangement, or position of the screen.

Having thus fully described my said invention, what I claim as new, and desire to secure by Letters Patent, is—

1. The combination, with the trunk or chute of a pneumatic straw-stacker, of a horizontal screen positioned within said trunk or chute and fixedly secured thereto just above the bottom thereof, said screen being composed of sheet metal crimped transversely into a saw-tooth form, with perforations at the lower points of the resulting pockets, substantially as shown and described and for the purposes set forth.

2. The combination, with the trunk or chute of a pneumatic straw-stacker, of a horizontal sheet-metal screen arranged therein and fixedly attached thereto just above the lower side thereof, said screen being formed with pockets produced by crimping the metal into

saw-tooth form, said pockets having perforations therein at the lowest points below the overhanging upper points, substantially as set forth.

3. The combination, with the trunk or chute of a pneumatic straw-stacker, of a screen therein for the purpose of separating grain from the straw passing over the same, said screen being formed with pockets into which the grain is adapted to fall, and said pockets having perforations at the lower points through which the grain may pass, said screen being fixedly attached to and within the conveyer trunk or chute beginning at or near the lower end and extending a suitable distance upwardly along the same, the trunk or chute having a suitable outlet from below said screen through which the saved grain may be discharged, the whole being constructed, arranged and operating substantially as set forth.

In witness whereof I have hereunto set my hand and seal, at Indianapolis, Indiana, this 11th day of February, A. D. 1899.

JAMES A. WALSH. [L. S.]
